UNITED STATES PATENT OFFICE.

FRANKLIN S. MCKENNEY, OF DETROIT, MICHIGAN.

COLLAR-FASTENER.

1,185,815.

Specification of Letters Patent.

Patented June 6, 1916.

Application filed November 25, 1912. Serial No. 733,389.

To all whom it may concern:

Be it known that I, FRANKLIN S. MCKENNEY, a citizen of the United States of America, residing at Detroit, in the county of Wayne and State of Michigan, have invented certain new and useful Improvements in Collar-Fasteners, of which the following is a specification, reference being had thereto in the accompanying drawings.

10 The invention relates to collar fasteners and is more particularly designed for use as a substitute for the stud at the rear of the collar band.

It is the object of the invention; first, to facilitate the engagement of the holder with the button hole in the neck band of the shirt; further, to do away with the discomfort from the pressing of the collar stud against the back of the neck, and at the same time to securely hold the collar in position; and further, to facilitate the adjustment of the tie and the retention of the same within its proper place between the folded portions of the collar.

25 In the drawings: Figure 1 is a perspective view, showing the manner of engaging the fastener with the collar band; Fig. 2 is a cross section, showing the initial engagement with the collar; Fig. 3 is a similar view with the collar fully secured; Fig. 4 is a rear elevation thereof part of the collar being cut away; Fig. 5 is a sectional plan view; and Fig. 6 is an elevation showing a modified construction.

30 Collar bands of shirts at the present time are usually constructed with the rear button-hole formed in a flap or ply overlapping the main band. This forms a bearing on the band for the base of the collar-button, but, owing to laundry, the insertion of the button is sometimes rendered difficult by the adhesion of the flap to the body of the band. Furthermore, although some of the pressure against the back of the neck is relieved by the imperforate band, the pressure is nevertheless often uncomfortable, while the adjustment of the tie over the stud is difficult. With my improved construction, the fastener may be readily engaged with the flap even when the latter is starched down, and after full engagement with the band and collar, all objectionable pressure upon the neck is avoided, and furthermore, the necktie glides around free and 55 is easily adjustable.

In detail, A is an engaging portion, preferably provided with a wedge-point B for opening and insertion beneath the collar flap; C is an outwardly curved or bulging portion connected with the portion A by a narrow neck D; and E is a laterally enlarged loop-portion adjacent to the portion C. As preferably constructed, and as shown in Figs. 1 to 5 the fastener is formed of wire, the end portions of which are bent to 60 form a portion A, which can be readily inserted into button-hole and retained from accidentally dropping out, and are then twisted together to form the portion D, beyond which the two strands separate to form 70 the portion C and finally the loop E. In Fig. 6, the fastener is formed from a sheet metal blank of similar shape. With both constructions the outwardly bulging or curved form of the central portion C will 75 engage the collar and hold it from movement, either upward or downward.

In use, the fastener is engaged with the collar band by inserting the point or nose B beneath the flap and then pressing inward 80 until it passes through the button-hole F. The end portion A is then inserted through the button-hole G of the collar H, after which the fastener is turned until the portion E projects upward, fitting within the 85 folded parts of the collar band I. The position then assumed by the parts is shown in Fig. 3, and it will be noted that the bulging portion C forms a pair of shoulders J and K for the collar, preventing movement of 90 the same in either an upward or downward direction. The portion E is curved as shown in Figs. 1 and 5, the curvature being substantially the same as that in the collar band, so that it will lie within and between the flap 95 and body of the band without obstruction. The portion C, though bulging sufficiently to form the retaining shoulders for the collar, is nevertheless restricted in depth, so as to permit the tie to be drawn between the 100 outer and inner plies of the collar.

My improved construction may be manufactured at small cost, has an ornamental and pleasing appearance, is easily manipulated, and forms a secure collar-holding fastening device, combined with a free clearance and necktie gliding provision.

What I claim as my invention is:

1. A collar fastener, comprising a member having a portion adapted for insertion 110

through the button-hole and provided with an entrance point or nose, an outwardly-bulging and inwardly returning portion for engaging the collar, and a portion laterally enlarged to a greater width than the first-mentioned portion and adapted to lie between the collar band and its flap.

2. A collar fastener, comprising an entrance portion adapted for insertion through the button-holes and provided with a point or nose, a portion bulging outward and returning inward, and a portion laterally extending to a greater width than said entrance portion and curved to conform to the curvature of the collar band.

3. A collar fastener, comprising a wire loop, having a portion formed by the separate sides of said loop, bulging outward and returning inward to form opposed shoulders for preventing vertical adjustment of the collar, a head portion of greater width than said first-mentioned portion and connected thereto at one end and curved in conformity to the curvature of the collar band, a twisted portion connected to said first-mentioned portion at the opposite end thereof, and a laterally enlarged end portion connected to

said twisted portion and terminating in a nose or point.

4. A collar fastener, comprising successively a portion terminating in a nose or point, a narrow portion, a portion bulging outward and returning inward to form opposed shoulders for preventing vertical adjustment of the collar, and a head portion of greater width than said bulging portion, curved in conformity with the curvature of the collar band.

5. A collar fastener, comprising a portion adapted for insertion through a button-hole, an outwardly-bulging and inwardly-returning portion adapted for insertion through the same button-hole, and a head portion of greater width than said bulging portion, said head portion and said first-mentioned portion extending in substantial alignment with each other.

In testimony whereof I affix my signature in presence of two witnesses.

FRANKLIN S. MCKENNEY.
